TOY AIRPLANE

Henry Hinton, Fleming, Ky.

Application May 22, 1945, Serial No. 595,103

3 Claims. (Cl. 46—76)

1

This invention relates to improvements in toy aeroplanes.

One object of the invention is to provide a toy aeroplane in which the propeller will be caused to turn substantially continuously, although alternately in opposite directions, by raising and lowering the aeroplane body.

A further object of the invention is to provide an inexpensive driving arrangement for the propeller shaft of a toy aeroplane whereby, as the plane body is raised and lowered, the shaft and propeller will be rotated alternately in opposite directions.

As a still further object, the invention contemplates a toy consisting of a support from which the aeroplane body is suspended so as to be raised and lowered, the propeller shaft having lengths of cord wound thereon in reverse directions whereby, as the plane is raised, one cord will be wound around the shaft while the other is unwound, and as the plane is lowered the first mentioned cord will be unwound while the second cord is rewound on the shaft, these operations being repeated as often as desired to turn the shaft and propeller alternately in opposite directions.

With these and other objects in view, the invention consists in certain details of construction and combinations and arrangements of parts, all as will hereinafter be more fully described and the novel features thereof particularly pointed out in the appended claims.

In the accompanying drawing—

Figure 1 is an elevational view of a toy aeroplane and its suspension support with the aeroplane, which is shown partly in section, illustrated in its lowered position; and

Fig. 2 is a similar view showing a modified form of the invention.

The body of the aeroplane is indicated at 10 and journaled in the body and extending longitudinally thereof is a spindle 11 which constitutes the propeller shaft on which the propeller blades 12 are mounted. The body 10, with associated structural parts such as the wings, rudder and the like may, of course, be of any desired style, design, or configuration.

In the form of the invention illustrated in Fig. 1 the propeller shaft 11 is adapted to be rotated alternately in opposite directions by lengths of cord A and B which are adapted to be wound on the spindle 11 in opposite directions. The free end of cord B is anchored to the crossbar 19 of a supporting structure. Crossbar 19 may be located at any desired height, depending upon the length of the standards (not shown) on which it

is mounted. The free end of the other length of cord A is adapted to be used for raising and lowering the plane and, for this reason, cord A is preferably threaded through an eye member 18 secured in the cross-bar 19 while the free end of cord B is attached to an eye 18a also secured in the cross member. Cord A is substantially twice the length of cord B so that there can be a series of convolutions of cord A wrapped around spindle 11 in one direction when the plane is in its lowermost position, as shown in Fig. 1. When in this position the length of cord B may be substantially fully unwound from the spindle. However, if the child playing with the toy pulls on the free end of length A of the cord the plane will not only be elevated but the convolutions of the length A of cord originally on the spindle will unwind with the result that the spindle 11 will turn and wind the length B of cord thereon while the plane is being elevated. When the plane has been raised to its uppermost position the length A of cord may be substantially completely unwound while the entire length of cord B will be wound around the spindle 11 in a direction opposite to the winding of the original convolutions of the length A of cord. As a consequence, when the child slackens the length A of cord to permit the plane to descend spindle 11 will be caused to turn in the opposite direction by the convolutions of the length B of cord with the result that the length B of cord is unwound and the length A of cord rewound to restore the parts to the positions and conditions in which they are illustrated in Fig. 1.

35 In the modified form of the invention illustrated in Fig. 2 the body 10 of the toy is attached to the lower end of a suspension cord or cable 13 by which the plane can be raised and lowered, the cord 13 being adapted to run through an eye 18b in the cross member 19 in the same fashion as cord A is operated in the previously described form of the invention. Attached to the shaft 11 are two impeller cords or cables 14, 16, which are adapted to be wound in opposite directions on shaft 11 with their free ends extending through suitable openings in the bottom of the plane. Cord 14 is of a length double that of cord 16 and attached to the free end of cord 16 is a weight 17 so that by anchoring the free end of cord 14 and raising the plane upwardly from the point of anchorage, cord 14 will unwind and turn shaft 11 with the result that the reversely disposed cord 16 will be wound up on the shaft. Similarly, after cord 16 has thus been wound on the shaft, if the plane is then lowered, weight 17 causes the shaft

11 to turn in a reverse direction and wind cord 14 on the shaft.

For instance, as shown in Fig. 2, when the plane is in its lowered position with cord 14 wound on shaft 11 and with the free end of that cord anchored to the ground or other surface as by a weight 15 heavier than weight 17, an upward movement of the plane will cause the shaft 11 to turn by reason of weight 15 being heavier than weight 17 with the result that cord 16 will be wound on the shaft in a direction opposite to the windings of cord 14. This shaft, together with blades 12 will continue to rotate until the plane is raised the full length of cord 14. After the plane has reached its uppermost limit of movement, it is then lowered and as cord 14 is thus slackened it is rewound on the shaft by the action of weight 17 which causes the cord 16 to unwind. Thus shaft 11 and blades 12 are revolved in the opposite direction until the weight 17 comes to rest on the ground or other surface, this being the lower position of the plane as illustrated in Fig. 1.

As will be appreciated, a child playing with the toy can raise and lower the plane repeatedly and in this way cause the propeller blades to revolve substantially continuously, although alternately in opposite directions to simulate a plane in flight. By using a weight on the longer cord 14 heavier than the weight on cord 16 for anchoring the otherwise free end of the longer cord, the toy can be operated in the house as well as out of the house. For instance, as indicated, with the elevating cord A or 13 free to run through an eye fastened in the crossbar 19 of the supporting structure located the proper distance above the floor or ground surface the crossbar can be located a considerable distance above the ground, much higher than a child could reach, and the plane raised and lowered by the child holding the free, depending end of the operating cord 13. In this way, the plane is capable of what might be considered by the child rather extended flights, all of which will increase the appeal of the toy to young children.

What I claim is:

1. In a toy aeroplane comprising a body and a propeller shaft journaled therein, a driving cord having one end attached to said shaft and wound on said shaft, a second driving cord having one end attached to said shaft and wound in the reverse direction on said shaft, weights attached to the free ends of said cords extending outwardly and downwardly from the body, one of said cords being of greater length than the other and the

5 weight attached to the longer cord being adapted to rest on a base and being heavier than the weight attached to the shorter cord, both of said cords being movable relative to the body, and means for raising and lowering said body.

2. In a toy aeroplane comprising a body and a propeller shaft journaled therein, a cord attached at one end to said shaft adapted to be wound on said shaft by rotary motion of the shaft in one direction, a weight attached to the other free end of said cord, a second cord having one free end and its other end attached to said shaft and adapted to be wound on the shaft by reverse rotation of said shaft, said second cord being double the length of the first cord, a second heavier weight attached to said second, longer cord adapted to rest on a base, said cords being movable relative to said body and extending outwardly and downwardly therefrom whereby when the plane body is raised above the heavier weight the full length of the cord attached to said heavier weight the shorter cord will be fully wound on said spindle and when the plane is lowered from said raised position the weight on the shorter cord will unwind the latter and wind the longer cord on said shaft.

3. In a toy aeroplane apparatus comprising an aeroplane body having a propeller shaft journaled therein, a supporting structure, means for suspending said body from said support and alternately raising and lowering the body relative to said support, a cord wound on said shaft and having one end attached to said shaft, a weight suspended from the other end of said cord below said body, and a second, longer cord wound in the opposite direction on said shaft and having one end attached to said shaft and its other end anchored below said body, whereby when the body is raised on its support the anchored cord will wind the weighted cord on the shaft and when said body is lowered from its raised position the weighted cord will wind the anchored cord on said shaft.

HENRY HINTON.
